UNITED STATES PATENT OFFICE.

JESSE CASPER MORRIS BROWN, OF PHILADELPHIA, PENNSYLVANIA.

INCANDESCENT ELECTRIC LAMP AND SOCKET.

SPECIFICATION forming part of Letters Patent No. 703,717, dated July 1, 1902.

Application filed February 28, 1902. Serial No. 96,088. (No model.)

To all whom it may concern:

Be it known that I, JESSE CASPER MORRIS BROWN, a citizen of the United States, residing at the city of Philadelphia, in the county 5 of Philadelphia and State of Pennsylvania, have invented certain new and useful Improvements in Incandescent Electric Lamps and Sockets, of which the following is a specification.

10 My invention has relation to a socket connection for an incandescent electric lamp; and in such connection it relates more particularly to the construction and arrangement of the lamp and the socket for receiving the same.

15 The principal objects of my invention are, first, to provide a socket for an incandescent electric lamp, comprising, essentially, an insulating-base from which projects vertically a series of flat springs or spring-fingers ar-

20 ranged in the form of a tube to receive and hold the neck of a lamp under spring tension, one of the vertical flat springs or fingers forming one terminal for the electric current, and in conjunction with these vertical spring-fingers the base is provided with a horizontal flat finger, forming the other terminal of the current and adapted to rest under spring tension upon the under face of the neck of the lamp when the lamp is placed in the socket,

25 and, second, to provide, in conjunction with such a socket, a lamp having on its neck a metallic sleeve connected with one end of the incandescent body within the lamp and on its base a terminal for the other end of said incandescent body, the metallic sleeve adapted to contact with the vertical contact spring-finger forming part of the socket and the base-terminal adapted to rest on the horizontal finger of the socket when the lamp enters said

30 socket.

The nature and scope of my invention will be more fully understood from the following description, taken in connection with the accompanying drawings, forming part hereof, 45 in which—

Figure 1 is a front elevational view of a lamp and socket embodying main features of my invention. Fig. 2 is a transverse sectional view, partly in elevation, illustrating the construction and arrangement of the lamp neck and socket. Fig. 3 is a top or plan view of the socket with the lamp removed; and Fig.

4 is a transverse sectional view of the socket taken on the line 4-4 of Fig. 3, but with the neck of the lamp in the socket.

55

Referring to the drawings, *a* represents the base of the socket, made of insulating material. From the upper face of the base *a* project the vertical spring-fingers *b*, one of which, *b'*, is connected to one terminal *d* of the electric current in any suitable manner. Each spring-finger *b* and *b'* is arranged independently of the others and is bent outward at its upper end, as at *b*², so as to more readily permit of the insertion of the neck of the lamp 65 *A* and to lock the fingers *b* and *b'* against the side of the neck, as hereinafter more fully described. From the base *a* of the socket also projects the horizontal flat finger *e*, to which the other terminal *d'* of the current 70 is connected in any suitable manner. This horizontal finger *e* is yielding or resilient and rests under spring tension upon the base of the lamp-neck when the lamp is in the socket. From the base *a* also projects the sleeve or 75 collar *f*, having an inner insulating-face surrounding the vertical spring-fingers *b* and *b'* and serving not only as a protection for the fingers, but also as a finish for the socket. The lamp *A* has a neck *g*, surrounded by a plain metallic sleeve *g'*, and on its base is provided with a plate or terminal *g*². One end of the filament *h* within the lamp extends to the sleeve *g'* and the other end to the plate or terminal *g*², as clearly illustrated in Fig. 2. 85

In operation when the neck *g* of the lamp is slipped into the socket the metallic sleeve *g'* rests substantially flat against the body of the spring-fingers *b* and *b'*, and especially against the finger *b'*, which is one terminal 90 for the electric current. The bends *b*² of the springs *b* and *b'* snap into the neck above the sleeve *g'* to prevent accidental withdrawal or displacement of the lamp in the socket. The terminal plate *g*² of the lamp-neck rests upon 95 the flat horizontal finger *e* of the socket, and when wholly within the socket the base of the neck slightly bends or displaces this horizontal finger *e*, so that said finger will rest under spring tension upon the terminal plate *g*² to form a more intimate contact between the terminal *g*² and the finger *e*, which finger, as hereinbefore explained, is connected with the other terminal of the cur-

100

rent. Should, for instance, grease, dirt, or rust form on either the terminal plate g^3 or finger e or upon the sleeve g' or vertical finger b' , a slight turning of the lamp in the 5 socket will remove these obstructions to perfect contacts.

Having thus described the nature and objects of my invention, what I claim as new, and desire to secure by Letters Patent, is—

- 10 1. An incandescent-electric-lamp socket, comprising a flat ring-shaped base of insulating material, a series of independent spring-fingers supported at their base upon and insulated from each other by the upper face of 15 the insulating-base and projecting upward therefrom to form in series a tubular socket to receive the lamp-neck, a terminal for the current connected directly to one of said spring-fingers, a flat spring-finger supported 20 upon the face of the insulating-base and projecting inward parallel to said face and over the opening in said base, and a second terminal for the current connected directly with the flat spring-finger.
- 25 2. In an incandescent electric lamp and socket, a socket comprising a flat ring-shaped insulating-base, a series of independent spring-fingers supported upon and insulated from each other by said base and projecting

upward therefrom to form in series a tubular socket, a terminal for the current secured directly to one of said fingers, a flat spring-finger supported upon the insulating-base and projecting inward over the opening in said base, a second terminal connected with 35 said flat spring-finger, a solid collar or sleeve supported upon the insulating-base and projecting upward therefrom, said collar or sleeve surrounding the vertical fingers and having an inner insulating-face adjacent to 40 said fingers, in combination with a lamp having a neck and an inclosed incandescent body, a plain metallic sleeve surrounding the neck and connected directly with one end of the incandescent body, said neck and sleeve 45 adapted to enter the vertical fingers of the socket, and a terminal plate formed on the base of the lamp-neck and adapted to enter the opening in the ring-shaped insulating-base of the socket to contact with the flat finger of said socket.

In testimony whereof I have hereunto set my signature in the presence of two subscribing witnesses.

JESSE CASPER MORRIS BROWN.
